ANDIRON

Harold H. Gilbert, La Honda, Calif.

Application June 28, 1950, Serial No. 170,905.

6 Claims. (Cl. 126—298)

1

This invention relates to andirons.

Andirons as presently designed for use in domestic fireplaces, merely provide support for one or more logs to raise them above the hearth of a fireplace. While serving this limited purpose adequately, conventional andirons are inefficient from the standpoint of utilizing radiant heat from burning logs.

A moment's reflection will indicate that the major source of useful heat given off by burning logs in a fireplace is radiant heat emitted by the burning or incandescent logs. Convection cannot play an important part in transfer of heat from a fireplace to a room or other space which is being heated, because the draft necessary for operation of the fireplace is from the room into the fireplace, thence upwardly through the flue.

It is a readily observable fact that the hottest, incandescent part of burning logs supported upon andirons is the under-surface of the logs. It is precisely this area, however, which is shielded from direct radiation to a room or other space which is being heated.

It has been proposed heretofore, in Low, United States Patent No. 890,669, granted in 1908, to provide andirons in which the logs are supported upon rods which are pitched at an angle and which extend upwardly and outwardly from the main standards or posts of the andirons. In principle, this construction is superior. However, from a practical standpoint it fails in that continued combustion of the radiating logs is faulty and defective.

It is, therefore, an object of the present invention to provide andirons which will support burning or incandescent logs so as to radiate heat efficiently into a room or other space which it is desired to heat, such andirons being also provided with means for maintaining combustion of the radiating logs.

It is a further object of the invention to provide andirons of a character which will support a second or auxiliary log in a position to maintain combustion of the main or radiating logs.

It is a further and particular object of the invention to provide andirons which satisfy the objects as set forth hereinabove, and which are also easily and economically constructed, assembled, disassembled and manipulated.

It is a further particular object of the invention to provide an andiron satisfying the objects indicated hereinabove and which can be constructed inexpensively from standard shapes and with a minimum of welding and/or other manufacturing operations.

2

These and other objects of the invention will be apparent from the ensuing description and the appended claims.

One form of the invention is illustrated by way of example in the accompanying drawings and is described in detail hereinafter.

In the drawings:

Figure 1 is a front elevation of the preferred form of andirons constructed in accordance with my invention.

Figure 2 is a side elevation of the andirons of Figure 1.

Figure 3 is a rear elevation.

Figure 4 is a top plan view.

Figure 5 is a perspective view of the removable cross-bar employed with my andirons.

Figure 6 is a fragmentary sectional view of the cross-bar of Figure 5.

Figure 7 is a perspective view of a modified form of cross bar, which is telescopic.

Referring now to the drawings, and more particularly to Figures 1 and 2 thereof, a pair of andirons, each generally designated as 10, are illustrated. Each of the andirons 10 comprises an upright post or standard 11. The post 11, as well as the other elements of the andirons, may be constructed of standard shapes such as square or round rods, thus eliminating the need for specially fabricated shapes. There is welded to the bottom of each of the posts 11 a main log supporting cantilever member or bar 12, which extends upwardly and outwardly from the post at approximately a 45° angle. Preferably, the bar 12 terminates at its outer end in a rounded tip 12a which has a decorative effect and also avoids an exposed sharp edge. Also, the rounded tips 12a assist in loading logs, as will be explained hereinafter. It will be seen that the bar 12, together with the post 11, forms a V-shaped cradle 13 which is intended to receive and support one end of a supply of logs 14 whose main radiating surfaces are at 14a.

An auxiliary rod 15 is also provided for each andiron and is welded at its inner end to approximately the mid-portion of the post 11. It extends forwardly and downwardly therefrom at 16 and upward and outwardly at 17, thereby forming a knee at 18. Legs 19 and 20 are provided, as illustrated, the outer leg 20 being rounded at 20a for decorative effect, to prevent exposure of a sharp edge and to facilitate loading of logs.

The auxiliary bar 15, together with the main bar 12 thus provides a generally U-shaped, inwardly tapering cradle 25, which is intended to

receive what I call an auxiliary log shown at 26. The log 26 is preferably considerably smaller than the main logs 14 for reasons which will be explained hereinafter.

Referring now to Figures 1, 5 and 6, for the purpose of providing lateral support for the andirons 10, a cross-bar 27 is provided. The cross bar 27 may, as illustrated in Figures 1 and 5, be constructed as a single piece of fixed length. Alternatively, as illustrated in Figure 7, a telescopic cross bar 28 may be provided, comprising telescopic male and female sections 29 and 30, respectively. The special advantage of a telescopic cross bar is, that it can be adjusted for logs of varying lengths.

In either case, there is welded to each end of the bar 27 or 28, a coupling member 35 which is formed with a square socket 36 to fit over the square upper end of the post 11. If the posts 11 are round, their upper ends are preferably squared. Relative turning of the andirons and cross bar is thereby prevented.

Referring now more particularly to Figure 2, the andirons 10 are placed on a hearth 30 and on opposite sides thereof. They are fitted with the cross bar 27 (or 28) to provide lateral support. In the event that the telescopic cross-bar 28 is employed, the spacing of the andirons can readily be adjusted to the width of the hearth or the length of the logs. A fire may be kindled in any suitable manner, as by placing kindling material in the cradle 13, igniting it, and allowing it to burn until hot coals drop into the ash pit 40. When the kindling is burning properly, or after it has dropped into the ash pit in the form of hot coals and has thoroughly heated the andirons and the fireplace, one or more logs 14 will be placed in the cradle 13 by rolling them down the main bars 12. The rounded ends 12a assist in rolling and guiding the logs. Similarly, an auxiliary log 26 will be rolled onto the auxiliary rods 15.

The path of the draft is indicated by the broken line 37 and the direction of radiation by the arrows 38. It will be apparent that, as the main logs 14 burn and incandesce, their hot, radiant under surfaces 14a are free to radiate heat outwardly into the room or other space which is being heated. The auxiliary log 26 will create and maintain a draft as indicated by the line 37. It will be apparent that this draft envelopes the main logs 14 and will keep them burning.

As a matter of actual experience, andirons of the character illustrated in the drawings and described hereinabove have been constructed and employed in a fireplace. A very marked improvement in the heating efficiency is readily noticed, and difficulties in maintaining the main logs 14 in a burning, incandescent state are obviated by providing and supporting an auxiliary log in the manner illustrated. It will also be apparent that the andirons 10 of my invention provide a main ash pit 40 for the main logs 14 and an auxiliary ash pit 41 for the auxiliary log 26.

It will thus be apparent that a novel type of andiron has been provided which is very simple in its construction and operation. It is easily manufactured from standard shapes and can be collapsed to occupy a very small amount of space, thus facilitating shipment and storage. The parts are easily set up and, when the telescoping cross-bar of Figure 7 is employed, are readily adjusted to fireplaces of different widths.

The andirons operate very efficiently, both from the standpoint of radiating the heat outwardly into a room or space which is being heated, and maintaining combustion of the radiating logs.

Other particular operating advantages of my andirons are as follows: The logs 14 automatically roll downwardly toward the hottest part of the fire, i. e., toward the bottom of the cradle 13, as the lowermost log 14 is consumed. The andirons may be, and preferably are placed at the rear of a hearth; therefore, smoking of the fireplace is very unlikely to occur. The fire provided by my andirons is a brighter, more cheerful fire than is provided by conventional andirons. Also, a single set or pair of andirons will fit a large fireplace as well as a small fireplace, and by supplying two different lengths of cross bar 27, or by using the telescopic bar 28, a single set of andirons can be used with short and long logs. In operation, all that is necessary after a fire has been kindled and the logs are burning, is to replenish the logs 14 and 26 occasionally, and this is facilitated by the downward slope and rounded ends of the bars or rods 12 and 15.

25 I claim:

1. An andiron comprising a main upright frame member, an upper bar extending outwardly therefrom for holding one end of a supply of main logs in an elevated position relative to the hearth of a fireplace and to allow heat from the under surface of the logs to radiate outwardly from the fireplace, and an auxiliary rod located beneath said upper bar and also extending outwardly from said main upright member, said auxiliary rod being located to support one end of an auxiliary log in a position to support combustion of said main logs.

2. An andiron comprising a main upright frame member, a main log supporting member fixed to said upright member and extending upwardly and outwardly therefrom to provide a V-shaped cradle for supporting one end of a supply of logs in an elevated position relatively to the hearth of a fireplace, and for access of radiation from the undersurface of said logs outwardly to a room, and an auxiliary log supporting member disposed beneath said main log supporting member and extending outwardly from said upright member for supporting one end of an auxiliary log beneath said main logs to support combustion thereof.

3. An andiron comprising a main upright frame member, a main log supporting member fixed to said upright member and extending upwardly and outwardly therefrom, and an auxiliary log supporting member located beneath said main supporting member and extending outwardly from said main upright member, said auxiliary member being formed with a knee concave toward said main supporting member for cradling and supporting one end of an auxiliary log beneath the main logs to support combustion thereof.

4. An andiron comprising a main upright frame member, a main log supporting member fixed to said upright member and extending upwardly and outwardly therefrom, and an auxiliary log supporting member located beneath said main supporting member and extending outwardly from said main upright member, said auxiliary member being formed with a knee concave to said main supporting member for cradling and supporting one end of an auxiliary log beneath the main logs to support combustion thereof, said auxiliary supporting member being formed

with a rounded leg at its outer end and with a leg adjacent said knee for resting upon a hearth and supporting the auxiliary member and log.

5. An andiron assembly comprising a pair of andirons each including an upright frame member and a log supporting member extending outwardly therefrom, and a removable cross-piece for extending between and engaging said upright members, said cross bar being provided with square sockets at its ends and said frame members being formed with square upper ends to receive said sockets.

6. A collapsible andiron assembly comprising a pair of andirons each comprising an upright frame member, a forwardly and upwardly projecting main log supporting member fixed thereto, an auxiliary log supporting member projecting forwardly from and fixed to said frame member beneath said main log supporting member to support an auxiliary log for maintaining 20

combustion of the main log, and a detachable cross bar for extending between said frame members and engageable with and detachable from the upper ends thereof to provide lateral support for the andirons.

HAROLD H. GILBERT.
